UNITED STATES PATENT OFFICE.

SAMUEL WALTERS, OF WARREN, PENNSYLVANIA.

CAR-DOOR.

1,051,790.

Specification of Letters Patent. Patented Jan. 28, 1913.

Application filed February 15, 1912. Serial No. 677,730.

To all whom it may concern:

Be it known that I, SAMUEL WALTERS, a citizen of the United States, and a resident of Warren, in the county of Warren and State of Pennsylvania, have invented a new and Improved Car-Door, of which the following is a full, clear, and exact description.

My invention relates generally to car door structures, and more particularly is directed to a new and improved construction whereby the door, when in closed position, lies flush with the outside of the car.

The principal object of my invention is to provide a new and improved car door embodying means whereby the door when in closed position will lie flush with the side of the car, means being provided for moving the door preparatory to opening it, suitable rails being provided whereby the door may be rolled to uncover the opening, the door moving into a position remote from the side of the door.

A further object of my invention is to provide a new and improved car door construction, the arrangement of the parts being such that communication between the interior of the car and the outside is prevented by the arrangement of the upper track on which the door moves, this track effectively closing the opening between the top of the door and the door casing.

Reference is to be had to the accompanying drawings, forming a part of this specification, in which like characters of reference indicate corresponding parts in all the views, and in which—

Figure 1 is a side view of the car door in closed position; Fig. 2 is a sectional view on the line 2—2 of Fig. 1, the door being in open position; Fig. 3 is a similar view, the position of the door previous to closing being shown; Fig. 4 is a similar view showing the door in closed position; Fig. 5 is a sectional view on the line 5—5 of Fig. 2; Fig. 6 is a sectional view on the line 6—6 of Fig. 2; Fig. 7 is a view showing the upper portion of the car door when in the position shown in Fig. 2; and Fig. 8 is a bottom plan view showing the detail of the arrangement of the rail and the shoe carried by the door.

Any suitable car comprising the side 2 is provided with an opening whereby access to the interior is had, the opening being adapted to be closed by the door 3 movably and slidably mounted in position, opposite

side walls of the opening being provided with pockets 4 into which the opposite side portions of the door are adapted to be seated when the door is closed, as shown particularly in Figs. 1 and 4.

The outside of the car adjacent the top and bottom thereof is provided with rails 5, 6, the lower rail 5 being positioned remote from the side of the car for the greater portion of its length by means of suitable braces 7, the end portion 8 of this rail being bent and being brought into engagement with the side of the car adjacent the lower portion of the opening. The upper rail 6 is preferably positioned on a suitable support 9 secured to the side of the car in any desired manner, the rail being bent similarly to the rail 5 and being substantially parallel therewith. Each of the rails 5, 6 is preferably of T-shape in cross section, as shown particularly in Fig. 5, the flanges of the rails being in engagement with the braces 7 and the support 9 respectively by any suitable means, such as bolts or screws 10.

Adjacent one end of the car door 3 and at the top and bottom thereof are the shoes 11, 12 secured to the door in any suitable manner, preferably by means of bolts 13, 14, the lower portion of the lower shoe 12 being recessed, as at 15, whereby it may embrace the lower rail 5, the opening being sufficiently large to provide for sliding movement of the shoe along the rail, but still being non-removable therefrom. The upper shoe 11 is slidably mounted in a casing 16 secured to the door so that movement of the shoe within the casing is permitted as the door is moved from open to closed position, the construction permitting a greater ease of operation due to the shoe adjusting itself to the rail in the event that the rail becomes bent or damaged from continued use. This shoe is also provided with a recess 100 adapted to embrace the rail 6 in a manner similar to the shoe 12. The opposite end portion of the door, and adjacent the top and bottom thereof and on the outside, is provided with fixed bearings 17 within which the rods 18, 19 are rotatably mounted, the rods being preferably separately made and held together in a manner substantially as follows: The lower end of the rod 18 is enlarged and provided with a substantially rectangular pocket 20, while the upper end 21 of the rod 19 is rectangular in cross section and engages the pocket 20, thereby providing for

- 22
- easy assemblage of the parts, turning of either rod insuring turning of the other rod by reason of such engagement. In order to turn the rod, a suitable lever 22 is pivotally mounted thereon at 23, the door being provided with a plurality of pockets 24 adapted to receive the end of the lever in open or closed position, whereby the maintenance of such position is insured.
- 10 The upper end of the rod 18 is provided with an off-set arm 25 which is in pivotal engagement with a shoe 26 which shoe is provided with a recess 27 whereby it may embrace the T-shaped upper rail 6 and slide therealong. The lower end of the rod 19 is provided with an off-set arm 28 in pivotal engagement with the shoe 29 by means of a pin 30, the shoe being provided with a recess 31 whereby it may embrace and slide along the lower rail 5.

15 Referring particularly to Fig. 5, it will be noted that the lower end of the rod 19 extends beyond the lower portion of the door 3, while the upper portion of the rod 18 extends below the top of the door 3, the side of the door being preferably provided with a suitable pocket 32 whereby ease of operation and non-interference of the parts is provided for.

20 From the above description it will be noted that the rails 5, 6 are fixed in position to the side of the car, while the rods 18, 19 are rotatably secured to the side of the door, it being clear that if either rod 18, 19 is turned, the door 3 will be moved closer to or removed from the side of the car, due to the off-set arms 25, 28 at the ends of the rods 18, 19. Referring more particularly to Fig. 2 which shows the door in open position, it will be noted that the door is adjacent the side 2 of the car. In order to bring the door into closed position, it is moved to the left, the rods 18, 19 and the arms 25, 28 thereof being in the position shown in Fig. 3, at the end of the travel. By turning the lever 22 the rods will be turned and the arms 25, 28 will swing the adjacent end of the door into the pocket 4 in the side wall of the opening, the door being then in closed position as shown in Fig. 4. In this position of the parts, the outside of the door is flush with the outside

of the car, and by reason of the engagement of the opposite ends of the door with the pockets 4, the goods within the car are protected from the elements and the door held more securely in position against removal. 55

Referring particularly to Fig. 8, wherein a detail view of the shoes 11, 12 is shown, it will be noted that the portions 11^a, 11^b of the bottom of these shoes are curved as at 11^c so that when the end of the door moves along the curved or bent portion of the tracks 5, 6, the curvature prevents binding of the parts and provides for easy operation 65 thereof.

70 The door may be provided with any suitable form of locking device, the preferred form embodying a hasp 40 having an opening therein engaging a suitable hook or staple 41 whereby withdrawal of the hasp 40 therefrom is prevented.

75 Of course, the particular size and shape, as well as the material of the different elements making up the structure of the car door may be varied, depending upon the size and structure of the cars with which it is used, such changes, however, being comprehended within the spirit of my invention.

Having thus described my invention, I 80 claim as new, and desire to secure by Letters Patent:—

85 Operating means for a car door in combination with rails along which the door travels, comprising a plurality of rods, one of the rods being provided with a pocket which engages one end of the other rod with a non-rotative engagement, the end portions of the said rods being provided with offset arms, the said offset arms engaging shoes mounted on the said rails, one of the rods being provided with a pivoted lever, and the door being provided with a number of pockets any one of which is adapted to engage the said lever, whereby the position of the rods 95 and the said offset arms is maintained.

90 In testimony whereof I have signed my name to this specification in the presence of two witnesses.

SAMUEL WALTERS.
